Primary Examiner—Jeffrey Asch(74) *Attorney, Agent, or Firm*—Jones, Day, Reavis & Pogue(57) **CLAIM**

We claim the ornamental design for a guard for a cut-off tool, as shown and described.

DESCRIPTION

FIG. 1 is a perspective view of a guard for a cut-off tool, embodying the ornamental design of the present invention; FIG. 2 is a top view of the guard of FIG. 1; FIG. 3 is a bottom view of the guard of FIG. 1; FIG. 4 is a view of one side of the guard of FIG. 1; FIG. 5 is a view of an opposite side of the guard of FIG. 1; FIG. 6 is a front view of the guard of FIG. 1; and, FIG. 7 is a rear view of the guard of FIG. 1.

The broken line showings of FIGS. 1-7 are for illustrative purposes only and form no part of the claimed design.

1 Claim, 4 Drawing Sheets**OTHER PUBLICATIONS**

Copy of a 1-page single-sided undated Campbell Hausfeld catalog sheet labeled "Air Powered Cut-Off Tool" and "TL1035", showing a prior art design. Prior to Aug. 18, 2000.

Copy of a 1-page single-sided undated Campbell Hausfeld catalog sheet labeled "Air Powered Cut-Off Tool" and "PL2535", showing a prior art design. Prior to Aug. 18, 2000.
